J. KOHN.
TOY BOAT,
APPLICATION FILED JULY 6, 1918.

1,300,177.

Patented Apr. 8, 1919.

UNITED STATES PATENT OFFICE.

JULIUS KOHN, OF NEW YORK, N. Y.

TOY BOAT.

1,300,177.

Specification of Letters Patent.

Patented Apr. 8, 1919.

Application filed July 6, 1918. Serial No. 243,693.

To all whom it may concern:

Be it known that I, JULIUS KOHN, a citizen of the United States, and a resident of the city of New York, borough of Manhattan, in the county and State of New York, have invented a new and Improved Toy Boat, of which the following is a full, clear, and exact description.

This invention relates to toys and has for an object the provision of an improved construction which requires some considerable skill and accuracy to fully enjoy the proper operation of the various parts.

Another object in view is to provide a toy in the shape of a ship or other article with movable parts, and a releasable catch for holding the parts together whereby when an object is thrown or shot against the catch the parts will be released for giving the effect of a boat being blown up by an explosive shell.

In the accompanying drawing:

Figure 1 is a top plan view of a toy disclosing an embodiment of the invention, certain parts being broken away for better illustrating the operating mechanism.

Fig. 2 is a section through Fig. 1 on line 2—2, the same being on an enlarged scale.

Fig. 3 is a view similar to Fig. 2, but showing the device in an open or knocked down position.

Fig. 4 is a detail perspective view showing the catch and associate parts.

Referring to the accompanying drawing by numerals, 1 indicates what may be termed a platform provided with a number of traction members 2 in the shape of wheels, there being preferably four wheels, though a greater or less number may be provided without departing from the spirit of the invention. On the platform 1 is positioned a member 3 which may be termed a base which is formed to represent the shape of a ship at the water line. Arranged on this base are sections 4, 5, 6 and 7. Sections 4 and 5 are connected to the base 3 by hinges 8 and 9, while sections 6 and 7 are connected to the base 3 by hinges 10 and 11. The various hinges just mentioned are positioned at the edges of the base so that the sections or parts 4 to 7 inclusive may be swung outwardly as shown by sections 4 and 5 in Fig. 3. The various sections are formed to give the appearance in the present instance of a battle-ship, though they may be formed to represent other forms of ships or even

other articles without departing from the spirit of the invention.

When the parts are in an assembled position they are arranged as shown in Figs. 1 and 2 with the catches 12 and 13 holding the sections together. Catch 12 is provided with a notch 14 at the lower end whereby holding extensions 15 and 16 are produced, said holding extensions setting on opposite sides of upstanding lugs 17 and 18 on plates 19 and 20. These plates are secured by screws or otherwise to the sections 4 and 5 as shown in Figs. 2 and 4, so that when the catch 12 is in position the sections 4 and 5 will be locked in an assembled position. Catch 13 operates identical with catch 12 and the parts are constructed identical, but this catch acts to lock the sections 6 and 7 while catch 12 acts to lock the sections 4 and 5.

Arranged at the upper end of catch 5 is a target 21, while a similar target 22 is arranged at the upper end of catch 13 so that when the parts are in the position shown in Figs. 1 and 2 and an article is thrown against either target the particular catch associated therewith will be dislodged and the springs 23 and 24 respectively will cause the various sections to move outwardly pivoted as shown in Fig. 3. These springs are secured in suitable recesses in base 3 and are compressed into the recess when the sections are assembled and continually tend to move upwardly so that when the catches are moved either by an article striking the targets or in any other manner the sections will be automatically and quickly thrown over to give in a limited sense the appearance of the ship having been torpedoed or blown up by some explosive. Preferably the targets are set up as shown and then the one playing with the toy will use a small gun and shoot at the targets. This will require accuracy in order to knock off either of the targets and when a player is given a certain number of shots it will be necessary to shoot straight in order to dislodge the same number of targets.

What I claim is:

1. A toy comprising a wagon structure, a base arranged on said wagon structure, a super-structure arranged on said base, said super-structure being divided into a plurality of sections, said sections being arranged in pairs, means for pivotally connecting each section to said base, a spring

- member acting on each section for moving the same to a given position, an upstanding lug on each section, said lugs being positioned so as to be arranged close together 5 when the sections are in a folded or assembled position, and a catch acting as a target formed with extensions straddling each pair of stops so that each catch and target will lock a pair of sections together.
- 10 2. A toy of the character described comprising a vehicle structure, a base mounted on the vehicle structure, said base being shaped to conform to the usual shape of a well known article, a super-structure mounted on the base conforming to the same well 15

known article above mentioned, said super-structure being divided into a plurality of pairs of sections, means for pivotally mounting each section on said base, an upstanding lug arranged on each of said sections, said lugs being positioned so as to be near each other when the sections are in a folded or assembled position, a catch for each pair of sections formed with an upright body having a notch in one end for accommodating the upstanding lugs on the sections, and a target connected with the end of said body opposite said notch. 20 25

JULIUS KOHN.
